METAL HOUSING FOR ELECTRICAL
CONTROL DEVICES

Harry A. Sedgwick, Shorewood, Wis., assignor to
Cutler-Hammer, Inc., Milwaukee, Wis., a corporation of Delaware

Application December 26, 1941, Serial No. 424,501

8 Claims. (Cl. 220—31)

This invention relates to improvements in metal housings for electrical control devices.

A primary object of the invention is to provide a novel form of hinged connection between the base portion and the cover portion of a metal housing of the aforementioned character.

Another object is to provide a novel and simple hinge connection between the cover and base portions of a metal housing enabling removal of the cover portion from the base portion upon a predetermined degree of opening of the former.

Another and more specific object is to provide a one-piece sheet metal hinge member which is rigidly and permanently attached to one of the housing portions and adapted for cooperation with the walls of an opening formed in the other housing portion.

Another object is to provide a hinge connection for the base and cover portions of a housing which is adapted for vertical mounting upon a wall or other suitable support.

Another object is to provide novel means for insuring proper placement of the hinge member or members with respect to the cover portion of a housing, whereby rigid attachment of said members to said cover portion, as by spot welding, is facilitated.

Another object is to provide a novel arrangement of parts whereby the hinge connections between the base and cover portions are substantially entirely concealed in the closed position of the cover portion.

Another object is to provide a novel form of latching device for use with a housing whose base and cover portions are so hinged, whereby the degree of telescoping or closing movement of the cover portion with respect to the base portion is predetermined.

Another object is to provide a novel arrangement of casing portions and hinges whereby at least ninety degrees of opening movement of the cover portion is required to provide for separation thereof from the base portion.

Another object is to provide novel and simple means whereby a cover portion having hinges of the aforementioned character may be rendered non-removable from the base portion of the housing, if desired.

Other objects and advantages of the invention will hereinafter appear.

The accompanying drawings illustrate certain embodiments of the invention which will now be described, it being understood that the embodiments illustrated are susceptible of modification in respect of certain structural details thereof

without departing from the scope of the appended claims.

In the drawings,

Fig. 1 is a view, on a reduced scale, partly in side elevation to show the latching means, and partly broken away to provide an interior view of the hinges affording a separable connection between the base and cover portions of the housing.

Fig. 2 is a fragmentary sectional view, normal size, on the line 2—2 of Fig. 1, showing the means for latching the cover in closed position and for limiting the degree of telescoping or closing movement of the latter.

Fig. 3 is a view, partly in section and partly in elevation, showing certain elements in the relative positions thereof illustrated in Fig. 2.

Fig. 4 is a fragmentary perspective view showing one of the members affording a hinged connection between the base and cover portions of the housing—the cover portion being shown in its closed position.

Fig. 5 is a fragmentary sectional view, on the line 5—5 of Fig. 1—with the cover portion of the housing in closed position.

Fig. 6 is a fragmentary sectional view quite similar to Fig. 5—but with the cover portion in its fully opened position—in which position it may be unhinged from the base portion.

Fig. 7 is a fragmentary sectional view similar to Figs. 5 and 6, but illustrating a slightly modified form of hinge, which is rigidly attached to the outer surface of the cover portion—whereby a closer fit between the cover and base portions of the housing may be provided.

Fig. 8 is a fragmentary perspective view similar to Fig. 4—but illustrating a slightly modified form of hinge—a portion of which is readily deformable at will to render the cover portion non-removable from the base portion.

Fig. 9 is a fragmentary elevational view, normal size, illustrating the depressions formed at predetermined points on one surface of that portion of the hinge opposite to the surface thereof which is attached to the cover—said depressions being formed as an incident to production of the extruded bosses on the opposite surface of the hinge.

Fig. 10 is a sectional view, on the line 10—10 of Fig. 9, illustrating the manner in which the hinge bosses are fitted into recesses formed in the adjacent surface of the cover portion, to insure proper positioning of the hinge prior to rigid securing of the hinge to the cover portion, as by spot welding.

Fig. 11 is a fragmentary elevational view of one of the hinges, showing the extrusions or bosses formed thereon, and

Fig. 12 is a fragmentary elevational view showing the recesses formed in the inner surface of the cover portion to accommodate the hinge bosses—the contour of the hinge being shown in dotted lines.

Referring first to that form of the invention shown in Figs. 1 to 6 and 9 to 12, the numeral 15 designates the base portion of a housing for an electrical control device—said base portion being formed in any suitable manner from a one-piece sheet metal blank to provide bottom side and end walls and an open front. A cover member 16 is also formed in any suitable manner from a one-piece sheet metal blank to provide top, side and end walls and an open back—the length of the side and end walls of the cover being such that the same is adapted to telescopically fit over or surround the side and end walls of base portion 15.

Although in the particular form of housing illustrated the cover portion 16 is shown as having a depth substantially equal to that of the base portion, it is to be understood that the hinges herein disclosed, by a slight reduction in the width of the portions thereof secured to one side wall or flange portion of the cover, may be used in conjunction with a metal housing wherein the top wall of the cover is adapted to seat against the front edge of the base portion.

The base portion 15 of the housing is provided in one side wall 15^a thereof with two or more relatively narrow substantially rectangular openings 17 and 18 which are longitudinally aligned with each other and spaced predetermined distances from the respective end walls 15^b and 15^c of base portion 15 and a predetermined distance from the front edge of said side wall.

The cover portion 16 has rigidly secured to the inner surface of side wall or flange 16^a thereof, as by spot welding, the flat portions 19^a, 19^b of a pair of like punched and stamped sheet metal hinge members 19, 19—said members 19 being spaced from each other a center distance corresponding to the center distance between said openings 17 and 18.

As illustrated in Figs. 1 and 4, although the height or vertical length of members 19 is only slightly less than the length of the respective openings 17 and 18, the arrangement is such that the body portions of members 19 are moved downwardly to effect offsetting thereof with respect to the horizontal walls of said openings 17 and 18 in the hinged or assembled relationship of the cover and base portions of the housing—the hinge members 19 being provided with downwardly opening substantially rectangular notches 19^c (see Fig. 4) to provide for such offsetting. Said notches are adapted to provide downwardly facing horizontal edges 19^b, 19^c which seat or bear against the lower end walls of the respective openings 17 and 18.

The hinge members 19 as produced have their intermediate portions 19^c (Fig. 4) bent or curved as shown, whereby the horizontal bearing edges 19^b thereof are in the form of a curve or arc to facilitate movement thereof through the openings 17 and 18 in opening or closing the cover portion 16 with respect to housing portion 15. The vertical walls 19^d of the aforementioned notches 19^c are adapted to abut or engage the inner surface of side wall 15^a upon opening of

cover portion 16 to limit the degree of opening movement of the latter—as best illustrated in Fig. 6.

As best illustrated in Figs. 4 and 5, members 19 have flat inner end portions 19^e—defined in part by the vertical walls 19^d of the respective notches 19^c—said flat end portions being angled toward the inner surface of the end wall 15^a to abut or engage the latter when cover portion 16 is in its closed position—the primary purpose of such engagement being to insure against rattling or noise produced by relative movement of the casting parts when in closed position.

With particular reference to Fig. 6, it is apparent that when cover portion 16 is fully opened the same may be readily removed from base portion 15 by merely lifting said cover vertically upward until the hinge members 19 are bodily aligned with the respective openings 17 and 18 (that is, when the upper edges of members 19 abut the upper end walls of the respective openings), whereupon the hinge members 19 may be withdrawn from said openings by lateral bodily movement of the cover portion 16 away from base portion 15.

Hinging connection of cover portion 16 to base portion 15 is effected with the parts in the last mentioned positions thereof—it being understood that when hinge members 19 are inserted inwardly through openings 17 and 18 to provide clearance between the edges 19^d, 19^d of the notches with respect to the inner surface of said wall 15^a of the base portion the cover portion may be lowered to provide for engagement of edge portions 19^b, 19^c of the notches with the respective lower end walls of said openings 17 and 18.

As will be apparent from Fig. 6, it is necessary that cover portion 16 be arranged at an angle displaced at least slightly more than ninety degrees from the closed position thereof to effect either hinging or unhinging thereof with respect to base portion 15—the lower end wall 16^c of cover portion 16 being required to clear both the side wall 15^a and the lower end wall 15^c of base portion 15 in each instance. This arrangement is advantageous in that it insures against any possibility of unhinging of cover portion 16 from base portion 15 except when the former is swung to substantially its extreme open position illustrated in Fig. 6; whereas the construction and arrangement of the hinges are such as to insure against "binding" or frictional engagement of the end walls of cover portion 16 with respect to base portion 15 during opening or closing movement of the former.

Referring more particularly to Figs. 9 to 12, it will be noted that each hinge member 19 has formed at predetermined points on its flat portion 19^a a pair of depressions 19^e and 19^f, as an incident to extrusion from the opposite surface of portion 19^a of a pair of substantially cylindrical bosses or projections 19^g and 19^h (Figs. 10 and 11). The side wall 16^a of cover portion 16 is provided at predetermined points on its inner surface with two like sets of depressions or recesses—one set of which is shown at 16^d and 16^e in Figs. 10 and 12. Said recesses 16^d and 16^e may be formed in any suitable manner, such as by milling or drilling the same, or by means of suitable pressure dies. In practice the recess 16^d of each set is preferably of substantially circular form in transverse cross section to freely receive, but with a rather close fit, the extrusion or boss 19^g; whereas the recess 16^e of each set

is preferably of elongated substantially elliptical contour, as shown. By this arrangement the manual insertion of bosses 19^i and 19^j into the respective recesses 16^d and 16^e is facilitated—it being understood that upon reception of boss 19^i by recess 16^d the boss 19^j will be received by recess 16^e at some point intermediate the length of the latter—whereby member 19 will be restrained against lateral movement in any direction with respect to side wall 16^a pending rigid attachment of the former to the latter, as by spot welding.

Also in practice the height of bosses 19^i and 19^j is slightly greater than the depth of the respective recesses 16^d and 16^e —such additional or excess height of said bosses being eliminated as an incident to spot welding of member 19 to side wall 16^a at said points, whereby the flat portion 19^a is brought into engagement with the inner surface of said side wall 16^a , as shown in Fig. 10.

The aforementioned means for limiting the degree of closing or telescoping movement of cover portion 16 with respect to base portion 15 of the housing preferably comprises an angle bar or bracket 20 , one portion 20^a of which is rigidly secured flatwise to the outer surface of side wall 15^d in a predetermined relationship to the contour thereof, as by spot welding, or in any other suitable manner. The portion 20^b of bracket 20 extends outwardly at substantially a right angle to portion 20^a thereof, whereby said portion 20^b is adapted to act as an abutment for the lower edge 16^g of side wall 16^f of the cover to limit the degree of closing movement of the latter, as shown in Figs. 1, 2 and 3.

A punched and stamped sheet metal latch member 21 is pivotally supported at a predetermined point upon the side wall 16^f of the cover as by means of a headed pin 22 —the upset shank end of which is shown at 22^a in Figs. 2 and 3; member 21 being offset inwardly, as shown at 21^a in Figs. 1 and 2 to accommodate the head of pin 22 and to provide for parallel spacing of the main body of member 21 a predetermined distance from the side wall 16^f . Member 21 is provided with an extension 21^b located in the plane of the main body thereof (Fig. 2); said extension having a forward curved cam edge 21^c (Fig. 1) which cooperates with the edge 20^e of bracket portion 20^b to effect counterclockwise rotation of member 21 as an incident to closing of cover 16 . Extension 21^b is further provided with a rearwardly angled cam edge 21^d (Fig. 1) which cooperates with the aforementioned edge 20^e of bracket portion 20^b to resiliently and releasably hold cover 16 in closed position, under the bias of a spring 23 , which tends to rotate member 21 in a clockwise direction, as herein-after described.

Spring 23 is preferably of substantially U-shape, as shown in Figs. 1 and 3—the same having an offset end portion 23^a which is inserted inwardly through an opening 16^a (Fig. 3) in side wall 16^f . The body portion of spring 23 is bowed or bent to extend around the pin 22 —the other end of said spring having an end portion 23^b which is bent to outwardly opening substantially semi-circular form to provide for pressure engagement with the shank of a pin 24 , between the head 24^a of the latter and member 21 ; the reduced shank end of pin 24 penetrating a corresponding countersunk opening in said member 21 and being upset against the walls of the countersink, and in a substantially flush relationship to the outer surface of member 21 , as

best illustrated in dotted lines at 24^b in Fig. 2. The spring 23 thus acts to bias member 21 to rotate in a clockwise direction,—whereas in the open position of cover portion 16 such rotation is limited by engagement of the head 24^a of pin 24 with the edge 16^i of a lug or tongue 16^j which is partially sheared and offset outwardly from said side wall 16^f (see Figs. 2 and 3). When cover portion 16 is in closed position the straight edge portion 21^e (Fig. 1) engages the aforementioned edge 20^e of bracket 20 to prevent clockwise movement of member 21 to the limit afore-described.

Member 21 is provided at its outer end with an outwardly extending flange 21^f to facilitate manual release of the latch against the bias of spring 23 —one or more fingers being placed behind said flange to provide for pulling or rotating member 21 in a counterclockwise direction. Member 21 is provided at its inner edge with an integral outwardly extending lug 21^g , which is positioned in slightly spaced parallel relation to the portion 20^b of bracket 20 when cover 16 is closed (Figs. 1 and 2). Lug 21^g and portion 20^b are provided with alined perforations, shown in dotted lines at 21^h and 20^d in said figures, to provide for insertion of the hasp or staple of a padlock through said openings, whereby the cover may be locked in closed position.

In Fig. 1 I have shown a pivoted handle 25 which provides for front operation of a motor starter or other switching or control device to be enclosed within the housing $15, 16$. Inasmuch as this operating mechanism forms no part of the present invention further description thereof is deemed unnecessary.

The upper and lower corners of the flat free end portions 19^e of the hinge members are preferably rounded or curved as shown at 19^k and 19^l (Figs. 1 and 4) to facilitate or initially guide the insertion thereof through the aforementioned openings 17 and 18 .

As will be apparent from consideration of Fig. 1; although I have herein disclosed the preferential use of a movable cover portion 16 carrying the hinge members 19 for cooperation with the openings 17 and 18 in the base portion 15 —it is obvious that by a slight modification the portion 16 might be utilized as the fixed or base portion of the housing, with the portion 15 serving as the cover portion telescoping thereinto—the hinges 19 and openings 17 and 18 remaining in the respective positions illustrated. In such a modification the handle 25 would be transferred to the portion 15 serving as a cover, whereas the latch member 21 and bracket 20 might be permitted to remain in the relative positions thereof illustrated.

In the device of Fig. 7, which may be assumed to be a sectional view similar to Fig. 5, the base portion 15 of the housing may be identical in size and shape with the corresponding portion aforementioned, and the same is preferably likewise provided with a pair of openings, one of which is shown at 18 . The cover portion 26 is substantially like the cover portion 16 aforementioned—except that the end walls (one of which is shown at 26^a) and the top wall 26^d are made slightly shorter than the corresponding walls of portion 16 , and preferably with a lesser degree of overlap of the cover portion 26 with respect to base portion 15 . This shortening is made possible by the fact that the side wall 26^a is adapted to fit quite closely against the side wall 15^a (Fig. 7), due to the fact that it is unnecessary to accommo-

date the flat portions 27^a of the punched and stamped sheet metal hinge members (one of which is shown at 27) therebetween. As shown in Fig. 7 the hinge members 27 are structurally and functionally quite similar to the members 19 aforescribed. However, since the flat portions 27^a of said hinge members 27 are attached by spot welding to the exterior surface of side wall 26^a of cover portion 26, said members are provided with intermediate curved portions 27^c and flat free end portions 27^e, corresponding to the portions 19^c and 19^e of members 19—whereas the flat end portions 27^a are connected with curved portions 27^c by substantially straight portions, designated by the numeral 27^x in Fig. 7, and arranged at a proper angle to the respective flat portions 27^a. The members 27 are notched or cut away beneath the intermediate portions 27^c and 27^x, as shown in dotted lines at 27^y and 27^z in Fig. 7, for the purpose aforescribed.

In the modification shown in Fig. 8, all parts may be like those shown in Figs. 1 to 6 and 9 to 12—with the exception that each hinge member 19 is additionally provided, preferably at the upper edge thereof as shown, with an upwardly opening notch 19^m—whereby an integral lug or tongue 19ⁿ is provided. After hinged assembly of the base and cover portions 15 and 16 of the housing the lugs 19ⁿ may be bent laterally, as by means of pair of pliers, to the position thereof shown in dotted lines in Fig. 8—said lugs 19ⁿ then acting to positively prevent unhinging of cover portion 16 from base portion 15 of the housing.

I claim:

1. As an article of manufacture, a one-piece punched and stamped sheet metal hinge member having a flat end portion, said portion having a plurality of bosses formed integrally with one surface to facilitate positioning thereof and rigid attachment thereof to one section of a metal housing, said hinge member having a second flat end portion arranged in a plane at an acute angle to the plane of said first mentioned end portion, the integral portion of said member between said flat portions being bent to arcuate form, said member having a notch formed in the lower edge thereof between said flat portions and underlying said arcuate portion, the upper end wall of said notch being adapted for sliding engagement with the bottom wall of an opening of suitable form in another section of the metal housing, one side wall of said notch being adapted to abut said last mentioned section under given conditions to limit the degree of sliding movement of said member in one direction, said second flat end portion having a notch formed therein and opening to one edge thereof to define a lug integral therewith, and said lug being bendable laterally after assembly of said housing sections in hinged relationship to each other to positively prevent unhinging thereof.

2. In combination, a metal housing comprising a base portion and a cover portion adapted for telescopic relationship to each other when in closed position, a straight side wall of one of said portions having a plurality of relatively narrow substantially rectangular openings formed therein in spaced relationship to the open end thereof, a corresponding number of one-piece punched and stamped sheet metal hinge members each rigidly and permanently secured at one end to the corresponding side wall of the other portion of said housing, each of said hinge members having a flat free end portion of a height only

slightly less than the height of the respective opening, the intermediate portion of each hinge member being bent to arcuate form in horizontal cross section, each hinge member having a downwardly opening rectangular notch of a width substantially coextensive with said portion of arcuate form, the arrangement being such that the free end portions of said hinge members may be jointly inserted through the respective openings and the hinge members then lowered to provide for sliding engagement of the end walls of said notches with the respective lower end walls of said openings, the side walls of said notches adjacent to the free end portions of said hinge members being adapted to act as stops to limit the degree of opening movement of said housing portions relatively to each other, and said housing portions being entirely separable from each other at said limit of opening movement thereof by sequential upward and lateral bodily movement of said hinge members relatively to said openings.

3. In combination, a metal housing comprising a base portion and a cover portion adapted for telescopic relationship to each other when in closed position, a straight side wall of one of said portions having a plurality of relatively narrow substantially rectangular openings formed therein in spaced relationship to the open end thereof, a corresponding number of one-piece punched and stamped sheet metal hinge members each rigidly and permanently secured at one end to the corresponding side wall of the other portion of said housing, each of said hinge members having a flat free end portion of a height only slightly less than the height of the respective opening, the intermediate portion of each hinge member being bent to arcuate form in horizontal cross section, each hinge member having a downwardly opening rectangular notch of a width substantially coextensive with said portion of arcuate form, the arrangement being such that the free end portions of said hinge members may be jointly inserted through the respective openings and the hinge members then lowered to provide for sliding engagement of the end walls of said notches with the respective lower end walls of said openings, the side walls of said notches adjacent to the free end portions of said hinge members being adapted to act as stops to limit the degree of opening movement of said housing portions relatively to each other, said housing portions being entirely separable from each other at said limit of opening movement thereof by sequential upward and lateral bodily movement of said hinge members relatively to said openings, and the telescopic relationship of said housing portions being such as to require at least substantially ninety degrees of opening movement thereof as a prerequisite to unhinging thereof.

4. In combination, a metal housing comprising a base portion and a cover portion adapted for telescopic relationship to each other when in closed position, a straight side wall of one of said portions having a plurality of relatively narrow substantially rectangular openings formed therein in spaced relationship to the open end thereof, a corresponding number of one-piece punched and stamped sheet metal hinge members each rigidly and permanently secured at one end to the corresponding side wall of the other portion of said housing, each of said hinge members having a flat free end portion of a height only slightly less than the

height of the respective opening, the intermediate portion of each hinge member being bent to arcuate form in horizontal cross section, each hinge member having a downwardly opening rectangular notch of a width substantially co-extensive with said portion of arcuate form, the arrangement being such that the free end portions of said hinge members may be jointly inserted through the respective openings and the hinge members then lowered to provide for sliding engagement of the end walls of said notches with the respective lower end walls of said openings, the side walls of said notches adjacent to the free end portions of said hinge members being adapted to act as stops to limit the degree of opening movement of said housing portions relatively to each other, said housing portions being entirely separable from each other at said limit of opening movement thereof by sequential upward and lateral bodily movement of said hinge members relatively to said openings, said hinges acting to limit the degree of telescoping of said base and cover portions at one side of said housing, and a bracket carried by one of said portions and engageable by an edge of the other portion to limit the degree of telescoping of said portions at the other side of said housing.

5. In combination, a metal housing comprising a base portion and a cover portion adapted for telescopic relationship to each other when in closed position, a straight side wall of one of said portions having a plurality of relatively narrow substantially rectangular openings formed therein in spaced relationship to the open end thereof, a corresponding number of one-piece punched and stamped sheet metal hinge members each rigidly and permanently secured at one end to the corresponding side wall of the other portion of said housing, each of said hinge members having a flat free end portion of a height only slightly less than the height of the respective opening, the intermediate portion of each hinge member being bent to arcuate form in horizontal cross section, each hinge member having a downwardly opening rectangular notch of a width substantially co-extensive with said portion of arcuate form, the arrangement being such that the free end portions of said hinge members may be jointly inserted through the respective openings and the hinge members then lowered to provide for sliding engagement of the end walls of said notches with the respective lower end walls of said openings, the side walls of said notches adjacent to the free end portions of said hinge members being adapted to act as stops to limit the degree of opening movement of said housing portions relatively to each other, said housing portions being entirely separable from each other at said limit of opening movement thereof by sequential upward and lateral bodily movement of said hinge members relatively to said openings, said hinges acting to limit the degree of telescoping of said base and cover portions at one side of said housing, a bracket carried by one of said portions and engageable by an edge of the other portion to limit the degree of telescoping of said portions at the other side of said housing, said bracket having an opening formed therein, a lug member carried by the other portion of said housing and adapted to be positioned in adjacent parallel relationship to said bracket when said housing portions are in closed position, and said lug member having an opening alined with said bracket opening to provide for insertion

through said openings jointly of a padlock hasp or other fastening member.

6. A metal housing for electrical control devices comprising, in combination, a rectangular box-like sheet metal base portion having an open front, a sheet metal cover portion having a peripheral flange adapted to surround said base portion adjacent to the open end of the latter, said base portion having a pair of vertically alined relatively narrow rectangular openings formed in one side wall adjacent to the front edge of the latter, a pair of punched and stamped one-piece sheet metal hinge members each having a flat portion rigidly attached to the cover flange at said side of the housing, each hinge member having an intermediate portion curved inwardly in convex relationship to the inner surface of said flat portion, each hinge member having a downwardly opening substantially rectangular notch formed therein and located beneath said curved intermediate portion, the horizontal end wall of each notch being adapted to slidably bear against the lower end wall of the opening respectively associated therewith, each hinge member also having a flat free end portion corresponding in length to said first mentioned flat portion and angled toward the plane of the latter, whereby said free end portion is adapted to abut the inner surface of the side wall of said base portion when the cover portion is in fully closed position, said free end portion defining one side wall of said notch which is adapted to abut said last mentioned inner surface in the fully opened position of said cover portion, said cover flange cooperating with said hinge members to positively prevent bodily separation of said cover portion from said base portion except when said cover portion is moved substantially ninety degrees from the fully closed position thereof.

7. A metal housing for electrical control devices comprising, in combination, a rectangular box-like sheet metal base portion having an open front, a sheet metal cover portion having a peripheral flange adapted to surround said base portion adjacent to the open end of the latter, said base portion having a pair of vertically alined relatively narrow rectangular openings formed in one side wall adjacent to the front edge of the latter, a pair of punched and stamped one-piece sheet metal hinge members each having a flat portion, said flat portions each having a pair of substantially cylindrical bosses extruded therefrom and projecting a predetermined distance from one surface thereof, the inner surface of said cover flange at said side of the housing having pairs of recesses formed therein to accommodate portions of the length of said bosses to facilitate positioning of said hinge members with respect to said cover portion, the excess length of said bosses being eliminated by fusion as an incident to spot welding at points alined with said bosses whereby said flat portion is brought into contact with said flange and rigidly attached thereto, each hinge member having an intermediate portion of arcuate contour in horizontal cross section, the lower end of each arcuate portion being cut away to provide a horizontal edge adapted to slidably bear against the lower end wall of the opening associated therewith and to provide a vertical edge which is adapted to abut the inner surface of said side wall to limit the degree of opening movement of said cover portion, and said cover portion in fully opened position being normally

bodily removable from said base portion by sequential upward and lateral movement of said hinge members relatively to said openings.

8. A metal housing for electrical control devices comprising, in combination, a rectangular box-like sheet metal base portion having an open front, a sheet metal cover portion having a peripheral flange adapted to surround said base portion adjacent to the open end of the latter, said base portion having a pair of vertically aligned relatively narrow rectangular openings formed in one side wall adjacent to the front edge of the latter, a pair of punched and stamped one-piece sheet metal hinge members each having a flat portion, said flat portions each having a pair of substantially cylindrical bosses extruded therefrom and projecting a predetermined distance from one surface thereof, the inner surface of said cover flange at said side of the housing having pairs of recesses formed therein to accommodate portions of the length of said bosses to facilitate positioning of said hinge members with respect to said cover portion, the excess length of said bosses being elimi-

nated by fusion as an incident to spot welding at points aligned with said bosses, whereby said flat portion is brought into contact with said flange and rigidly attached thereto, each hinge member having an intermediate portion of arcuate contour in horizontal cross section, the lower end of each arcuate portion being cut away to provide a horizontal edge adapted to slidably bear against the lower end wall of the opening associated therewith and to provide a vertical edge which is adapted to abut the inner surface of said side wall to limit the degree of opening movement of said cover portion, said cover portion in fully opened position being normally bodily removable from said base portion by sequential upward and lateral movement of said hinge members relatively to said openings, and means comprising a lug formed integrally with the free end portion of each hinge member, said lugs being bendable at will after hinged assembly of said base and cover portions to positively prevent unhinging of the latter from the former.

HARRY A. SEDGWICK.
